UNITED STATES PATENT OFFICE

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

WARNING-SIGNAL FOR GRADE INTERSECTIONS OF RAILWAYS AND HIGHWAYS.

1,316,516.

Specification of Letters Patent. Patented Sept. 16, 1919.

Application filed April 24, 1915, Serial No. 23,576. Renewed May 20, 1919. Serial No. 298,548.

To all whom it may concern:

Be it known that I, CLARENCE S. SNAVELY, a citizen of the United States, residing at Pittsburgh, in the county of Allegheny and State of Pennsylvania, have invented certain new and useful Improvements in Warning-Signals for Grade Intersections of Railways and Highways, of which the following is a specification.

10 My invention relates to warning signals for grade intersections of railways and highways, and particularly to signals of this type comprising a swinging arm.

15 I will describe one form of signal embodying my invention, and will then point out the novel features thereof in claims.

20 In the accompanying drawings, Figure 1 is a view showing one form of signal embodying my invention located adjacent a grade crossing of a railway and a highway. Fig. 2 is a view showing an elevation of the mechanism of the signal shown in Fig. 1 with the door of the casing thereof removed. Fig. 3 is a sectional view on the plane indicated by the line III—III of Fig. 2, looking in the direction of the arrows. Fig. 4 is a view showing in perspective a sleeve 18 shown in Figs. 2 and 3. Fig. 5 is a view showing more in detail an electromagnet 24 shown in Figs. 2 and 3. Fig. 6 is a view looking downwardly at the top of the parts mounted on shelf 14 of Figs. 2 and 3, certain of the parts on this shelf being removed for the sake of clearness. Fig. 7 is a view showing in perspective an armature 46 shown in Fig. 2. Fig. 8 is a view showing on an enlarged scale the circuit controller shown in Figs. 2 and 3. Fig. 8^a is a view showing the controller shown in Fig. 8 with one part in another position. Fig. 9 is a sectional view on line IX—IX of Fig. 8, looking in the direction of the arrows. Fig. 10 is a diagrammatic view showing one arrangement of circuits adapted to be used with the circuit controller shown in Figs. 8 and 9. Fig. 11 is a view showing more in detail a latching member 101 shown in Figs. 2 and 3. Fig. 12 is a sectional view on line XII—XII of Fig. 11, looking in the direction of the arrows. Fig. 13 is a perspective view showing a latching member or arm 136 shown in Fig. 2. Fig. 14 is a view showing in front elevation an armature-releasing de-

vice shown in Fig. 6. Fig. 15 is a view showing one form and arrangement of circuits 55 for controlling the signal shown in Fig. 1.

Similar reference characters refer to similar parts in each of the several views.

Referring first to Fig. 1, I have here shown a railroad track A crossed by a highway B. Adjacent the crossing and visible from the highway at a distance from either side of the crossing is a warning signal C embodying my invention. A pole 1 supports adjacent its upper end a bracket arm 2, to the outer end of which is fastened a casing 3 containing mechanism to be described hereinafter, by which a pendulum 4 can be made to oscillate. The bob of this pendulum consists of a disk 5 colored preferably red, upon both sides of which is painted in conspicuous letters the word Stop. By means of a latching mechanism to be described hereinafter, the pendulum can be locked in the inclined position shown in the 75 drawing, so that the word Stop on both sides of the disk is covered by two shields 6 attached to pole 1 so that disk 5 can enter the space between them. A red lamp 7 which is fixed to the lower end of disk 5 is 80 controlled as described hereinafter, so that it is illuminated when the pendulum is free to oscillate, but is extinguished when the pendulum is latched in the inclined position.

85 By means of controlling mechanism to be described hereinafter, pendulum 4 is unlocked upon the approach of a train and begins to swing; at the same time red lamp 7 is illuminated. This gives a very effective warning signal—the swinging red disk being 90 the equivalent of a flagman's danger flag and the swinging red light being the equivalent of a flagman's red lamp. According to the time of day, either the disk or the lamp is visible from a distance. Pendulum 95 4 swings until the train has reached the highway, then the latching device again becomes operative and locks the signal in the position shown on the drawing, so that the words Stop are covered and the red light is 100 extinguished. As pointed out hereinafter, in case of failure of any part of the mechanism, the pendulum hangs vertically or oscillates continuously, thus indicating that such failure has occurred.

105 I shall now describe the mechanism in-

closed by casing 3, with reference first to Figs. 2 and 3. A shelf 14 is fixed to the side walls of casing 3 by means of rivets 15 and serves as a support for a shaft 11 mounted 5 on the shelf in ball bearings 12 and 13. Pendulum 4 which extends into casing 3 through a slot S in the bottom of the casing, is suspended from and locked to shaft 11, the upper end of the pendulum being screwed into 10 a head 16 fixed to shaft 11 by pins 17. A sleeve 18 is locked to the shaft near its middle by means of a key 19. Sleeve 18 shown in perspective in Fig. 4, consists of two annular shaped portions 19^a and 19^b integral with 15 which is a central portion 21 which envelops the shaft only on its lower side, the top half of this portion having been removed so as to form faces 22 and 23. With reference to Fig. 2 it is clear that pressure 20 on face 22 or 23 of sleeve 18 tends to cause the pendulum to swing to the right, or to the left, respectively. These pressures are produced by electromagnetic means, as I shall now describe.

25 Electromagnets 24 and 25 are suspended from shelf 14 on the left and right side, respectively of shaft 11. As shown in Fig. 5 and Fig. 6, which is a plan view of part of shelf 14, electromagnet 24 comprises two 30 cores 31^a and 31^b, which are widened into pole pieces 32^a and 32^b at one end, and turned down to form shoulders 33 near the other end. The cores are slipped through a plate 34 of non-magnetic material provided with 35 two upwardly projecting ribs 35, whereby the cores are prevented from turning when the pole pieces rest against the surface of plate 34. Bobbins carrying the magnet winding 36 are slipped over cores 31^a and 40 31^b and are held in place by means of a back strap 37 and nuts 38 screwed over the ends of the cores. The assembled electromagnet is then attached by means of rivets 41 to shelf 14, so that plate 34 covers a corresponding hole in the shelf. Electromagnet 45 is of like construction and fastened to shelf 14 in a similar manner by a plate 34^a. In Fig. 7 I have shown a perspective view of armature 46 of electromagnet 25, which 50 is hinged to shaft 11 by means of holes 48 through the ends of arms 47 integral with the armature. Arms 47 are of such length that as shown in Fig. 2, armature 46 engages the pole faces of magnet 25, when it is swung 55 in a clockwise direction about shaft 11. Armature 45 is similar to armature 46 and hinged to shaft 11 in the same manner, so that, it engages the pole faces of magnet 24 when swung about the shaft in counter-clockwise direction. The armatures are prevented from moving longitudinally on shaft 11 as shown in Fig. 3, by means of sleeves 50 55 enveloping both ends of shaft 11 between bearings 12 and 13 and arms 47 of armatures 45 and 46 respectively. Each armature is

provided with a lug 49 for the purpose of engaging faces 22 and 23 respectively of sleeve 18, which as best shown in Fig. 3, is of such length that it fits loosely between one arm 47 of armature 45 and another arm 70 47 of armature 46. As pointed out hereinbefore, armatures 45 and 46 are free to turn about shaft 11, but sleeve 18 is keyed thereto. Consequently, when with reference to Fig. 2, armature 45 is moved counter-clockwise 75 about shaft 11 its lug 49 engages face 22 of sleeve 18, so that shaft 11 is rotated and pendulum 4 is swung from left to right. In a similar manner the pendulum is swung in the reverse direction when armature 46 is 80 rotated clockwise about shaft 11, so that its lug 49 engages face 23 of sleeve 18. Thus, if the pendulum is released from the position shown in Fig. 2 and armature 45 is attracted by electromagnet 24, pendulum 85 4 is acted upon not only by gravity, but also by the magnetic pull exerted on armature 45. It will be noted that the component of gravity tending to move the pendulum decreases from a maximum at the beginning 90 of the swing to zero at the middle position, whereas the magnetic pull increases from a small force at the beginning of the stroke to a maximum when the armature strikes the pole faces. At that point the pendulum 95 is free to continue its swing, because shaft 11 is free to turn counter-clockwise with respect to armature 45. The angle between pendulum 4 and armature 45 is made greater than 90°, so that when the pendulum arrives at the middle point of its stroke, and the component of gravity has become zero, armature 45 is still several degrees away from the pole pieces of its electromagnet, and the pendulum is still acted upon by a 100 force in the direction of the swing. The purpose of this is to start the pendulum from rest when in the vertical position as will appear hereinafter.

For controlling electromagnets 24 and 25 110 I provide a circuit controller D, (see Figs. 2 and 3) the terminal board 61 of which is of insulating material and is secured to standards 62 and 63 mounted on shelf 14. This circuit controller D is shown on an enlarged scale in Figs. 8 and 9, to which I will now refer. Shaft 11 is provided at its forward extremity with a collar 64 of insulating material, fixed to the shaft by any suitable means such as a pin 65. A casting 115 66 of electroconductive material is fastened to collar 64 by means of screws 67, so that casting 66 is rigidly attached to shaft 11, but electrically insulated therefrom. A shaft 68, fixed to casting 66 by means of a 120 pin 69 serves as a support for a second casting 71, which is rotatably mounted thereon and held in place by a cotter pin 70 in the end of shaft 68. Casting 66 is provided with two arms 72 and 73 carrying screws 125 130

75 which extend from casting 66 in such direction that they engage a lug 74 projecting from casting 71, so that the amount of rotation of the castings with respect to each other is limited to an angle which can be adjusted by screws 75. For a purpose which will appear hereinafter, casting 71 is furthermore provided with an arm 76 in the end of which is journaled a roller 77. Another roller 78 supported by a spring 79 fixed to terminal board 61 by means of a bolt 91, is adapted to engage roller 77 when casting 71 is rotated. Springs 81 and 82 are mounted on casting 66 so as to bear on projections 80 of casting 71 thus tending to hold lug 74 midway between arms 72 and 73. Casting 71 is provided with a sector 84, adapted to be engaged by either of two contact fingers 85 or 86 mounted on board 61 by terminal posts 85^a and 86^a respectively, and casting 66 is provided with a sector 83 adapted to be engaged by a contact finger 87, see Fig. 8^A, mounted on board 61 by a similar terminal post, which in Fig. 8 is directly behind post 86^a. All contact fingers and spring 79 are biased to bear against stops 88, mounted on terminal board 61. When either contact finger 85 or 86 engages sector 84 the contact pressure is of such value that the friction resulting therefrom when casting 71 is rotated, produces a torque which is greater than the torque exerted by spring 81 or 82 tending to hold arm 74 midway between arms 72 and 73 of casting 66. In other words, when the pendulum is swung from right to left, casting 71 is turned by screw 75 in arm 73, whereas, when the pendulum is swung from left to right, casting 71 is rotated by means of screw 75 in arm 72.

With reference to Fig. 10, the circuit for energizing magnet 25 is as follows: from a battery 99, through wire 101, contact finger 87, sector 83 of casting 71, shaft 68, casting 66, sector 84, finger 86, magnet 25 to battery 99. If sector 84 is turned so that it makes contact with finger 85, the circuit is completed through magnet 24. As I shall describe below when sector 84 breaks contact with one contact finger it immediately makes contact with the other contact finger. Accordingly, as long as sector 83 and finger 87 are in engagement, one of the magnets 24 or 25 is energized, according as sector 84 is in engagement with contact finger 85 or 86.

To describe the operation of the mechanism described hereinbefore, suppose that the pendulum is in the extreme left position shown in Fig. 2. Then sector 84 is engaged by contact finger 85, but sector 83 is not in engagement with finger 87, directly behind finger 86, so that both magnets are deenergized. When the pendulum is released by operation of mechanism to be described

hereinafter, it begins to swing to the right due to the action of gravity. When sector 83 is engaged by finger 87 the circuit for magnet 24 is completed, so that the magnetic force exerted on armature 45 assists gravity in moving the pendulum; this force increases as armature 45 approaches the poles of magnet 24. During the first part of the stroke casting 71 does not turn, because of the friction between contact finger 85 and sector 84. When, however, screw 75 in arm 72 strikes arm 74, casting 71 is turned by positive force to the right, so that the position of the sectors is as shown in Fig. 8^A when the pendulum reaches the middle of its stroke. As it passes through this position, due to the action of inertia and magnetic attraction, roller 77 strikes roller 78 and bends spring 79 outwardly until the centers of rollers 78 and 77 and shaft 68 are in a straight line. Then, due to the action of springs 79 and 82, casting 71 is suddenly pushed to turn counter-clockwise with respect to casting 66, so that sector 84 quickly breaks contact with finger 85 and immediately thereafter engages contact finger 86 at its other end, so that magnet 24 is de-energized and magnet 25 is energized instead. At this time armature 45 is resting on the pole faces of electromagnet 24, but armature 46 has been turned through a considerable angle away from the poles of magnet 25, so that the attraction of armature 46 is comparatively feeble. The inertia of the pendulum is of considerable magnitude, however, so that it overcomes the combined counter action of the magnetic attraction and gravity, and the pendulum continues in its stroke. When sector 83 leaves contact finger 87, the circuit of magnet 25 is broken, and the pendulum continues in its swing until all its kinetic energy has been expended. The return stroke is similar and need not be described here.

Suppose now that the pendulum instead of being released from the position in Fig. 2, hangs in the middle of its stroke, the parts of the circuit controller being in the positions shown in Fig. 8^A. Contact fingers 85 and 87 being in engagement with their respective sectors 84 and 83, magnet 24 is energized, and armature 45, being only a few degrees removed from the poles of magnet 24, is attracted with a force sufficient to move the pendulum slowly to the right against gravity and friction until, as explained hereinbefore, sector 84 suddenly breaks contact with finger 85 and engages contact finger 86, see Fig. 8. The resultant energization of magnet 25 causes the pendulum to reverse, for the kinetic energy of the pendulum is but small. Magnet 25 remains energized until roller 77 snaps past roller 78, then sector 84 breaks contact with finger 86 and makes contact with finger 85

so that magnet 24 is energized. This time the pendulum does not reverse immediately because it has acquired additional kinetic energy due to the initial potential energy at the beginning of the stroke. In this manner the stroke of the pendulum increases until the energy imparted to the pendulum by the electromagnet equals the loss of energy due to the resisting forces.

- 10 The latching apparatus mentioned hereinbefore by which the pendulum may be held in the position shown in Fig. 2 comprises a member 101 attached to the arm of pendulum 4. With reference to Figs. 11 and 12, member 101 comprises two plates 102 and 103 held parallel to each other by means of rivets 104, and adapted to slide in grooves 105 in a block 106. The arm of pendulum 4 is passed through a hole 109 in block 106, where it may be clamped by means of screws 111. Plates 102 and 103 are connected at one end by means of a strap 112, which forms a stop for a spring 114 fastened thereto by a bolt 113. The other end of spring 114 abuts block 106, so that the block is pressed against rivet 104. Member 101 is thus resiliently connected to pendulum 4, for a purpose which will appear hereinafter. Shafts 115 and 116 are passed through holes in plates 102 and 103 and are secured therein by means of cotter pins 117. These shafts support pawls 118 and 119 respectively, so that they are free to rotate through an angle limited by the engagement 30 of the pawl arms with the shanks of rivets 104. The pawls are biased by gravity to the position shown in Fig. 12, so that they are adapted to be engaged by mechanism which I shall now describe.
- 35 With reference to Figs. 2 and 6, an electromagnet 121 similar to magnets 24 and 25 is mounted in a similar manner on shelf 14. The armature 122 of magnet 121 is secured by screws 124 to a casting 123, which is pivoted on a shaft 126 fixed in standards 127 integral with shelf 14. Extensions 132 and 133 depending from shelf 14, see also Fig. 3, support a pin 134, which is surrounded by a sleeve 135. An arm 136, which as shown in 40 perspective in Fig. 13 comprises a block 137 to which are riveted parallel blades 138 and 139, is locked to the front end of sleeve 135 by a key 141 shown in Fig. 3. A roller 142 is mounted on a pin 143 in the end of arm 136, so that, when sleeve 135 is turned, this roller is brought into or out of the path described by pawls 118 and 119 when the pendulum is oscillating. An upwardly extending arm 144, see Figs. 2, 3 and 6, is keyed to 45 the rear end of sleeve 135 and is connected by a link 145 to an arm 146 integral with casting 123. Another arm 128 integral with casting 123 carries a counterweight 129 of sufficient mass to hold armature 122 away 50 from the magnet poles. To increase the re-

lease voltage of magnet 121, *i. e.*, the voltage at which the magnet is unable to retain the armature against its stop, I provide a lever 147, consisting of two blades, fulcrumed in a standard 148 on shelf 14. With reference 75 to Fig. 6 and to Fig. 14, which shows a side elevation of lever 147, one arm of the lever carries a weight 149; the other arm terminates in a tip 152 adapted to pry under an extension 151 on casting 123. In order to 75 hold armature 122 against the pole faces, magnet 121 must overcome the combined action of counterweight 129, and lever 147, which then is in the position shown in Fig. 14. But the movement of lever 147 is limited because after tip 152 has moved upward only a small distance, weight 149 rests against shelf 14, so that armature 122 is affected by weight 149 only during that portion of its stroke when it is nearest the pole 80 faces. In this manner lever 147 increases the release voltage of magnet 121, but does not affect its pick-up voltage.

To describe the operation of this apparatus, suppose that magnet 121 is deenergized so that its armature is away from the pole faces, due to the action of lever 147 and counterweight 129. Then arm 144, sleeve 135 and arm 136 will have turned clockwise from the positions shown in Fig. 90 2, so that roller 142 will be out of the path described by pawls 118 and 119 when pendulum 4 oscillates. If magnet 121 is then energized armature 122 will be attracted against the action of counterweight 129 and lever 100 147, so that the locking mechanism will be returned to the position shown in Fig. 2. If pendulum 4 is then swung to the left, pawls 118 and 119 successively hit roller 142 and, being free to turn to the right, do not 105 obstruct the path of the pendulum. But on the return stroke of the pendulum roller 142 is again engaged by pawl 119, which is, however, prevented from turning to the left by pin 104, so that pendulum 4 is arrested in 110 the position shown in Fig. 2. The momentum of the pendulum is gradually absorbed by spring 114, which is compressed so that the kinetic energy of the pendulum is slowly 115 decreased and the severity of the shock mitigated. If the amplitude of the swing of the pendulum is smaller, so that pawl 119 does not pass roller 142 as the pendulum swings to the left, then the pendulum is arrested by pawl 118. Similarly, if pawl 119 should stick in a disengaging position, the 120 pendulum would be arrested by pawl 118.

When the pendulum is latched up by pawl 119, contact segment 83 (Fig. 10) has left spring 87 so that both magnets 24 and 25 are deenergized, thus avoiding any unnecessary consumption of energy by the signal when the parts are at rest in the clear position. This is the chief function of the contact 83—87 although it performs the addi- 125 130

tional function of deenergizing magnets 24 and 25 when the pendulum is near each end of the stroke and the armatures are at the greatest distance from the magnet poles; the 5 pull on the armatures would be very small at such times and the energy consumption of the signal is materially reduced by deenergizing the magnets at those times.

It may be noted here that the line of action 10 of the pressure of pawl 119 on roller 142 passes but slightly to the right of the center of shaft 134, so that this pressure has but a small component tending to rotate arm 144 clockwise. Again, link 145 and casting 15 123 form a toggle, so that the force actually transmitted to armature 122, tending to raise it due to the pressure exerted on roller 142 is comparatively small.

Electromagnet 121 is controlled as shown 20 in Fig. 15. Reference character 151 designates the track rails of a railroad track A on which traffic moves in the direction of the arrow. B is a highway crossing the tracks and F designates a section of track 25 insulated from the rails on either end thereof by insulated joints 152. Section F is provided with a track circuit which as here shown comprises a battery 153 connected to the track rail at one end of the section and 30 electromagnet 121 connected to the track rails at the other end of the track section by wires 154 and 155. With no train in section F electromagnet 121 is energized by current from battery 153 and, as described 35 hereinbefore, holds pendulum 4 in the extreme left hand position. But when a train enters section F, magnet 121 is short-circuited so that it releases its armature 122. This causes pendulum 4 to be unlatched and to 40 oscillate due to its driving mechanism, until the train leaves section F, for then relay 121 is again energized, attracts its armature and causes pendulum 4 again to remain in the left inclined position.

If battery 153 in the track circuit fails, or, due to any other abnormal condition, magnet 121 is deenergized, or the latching mechanism *per se* is inoperative, pendulum 4 oscillates continuously, regardless of the 50 presence or absence of trains on section F. Similarly failure of battery 99 (see Fig. 10), or derangement of the mechanism whereby the pendulum is oscillated, causes the pendulum, after it has been released by 55 the latching apparatus, to come to rest in the middle position. In either case of failure the signal gives a warning indication to traffic on the highway. At the same time the signal maintainer can easily detect these 60 failures because of the evident abnormal results produced, so that even with superficial inspection, the signal is not liable to remain inoperative for a prolonged period of time.

For the control of lamp 7 attached to the 65 bob of pendulum 4 I have provided, see Fig.

2, a contact finger 176 fixed to and insulated from casting 123 and adapted to engage a contact block 200 when armature 122 is released. This is shown diagrammatically in Fig. 15 from which it is apparent that closure of contact 176-200 completes the circuit through lamp 7 and a battery 175, so that the lamp burns as long as magnet 121 is deenergized, in other words, as long as a train occupies section F.

Although I have herein shown and described only one form of apparatus embodying my invention, it is understood that various changes and modifications may be made therein within the scope of the appended 75 claims without departing from the spirit and scope of my invention.

Having thus described my invention, what I claim is:

1. In combination, a pendulum, two electromagnets for actuating said pendulum, one for each direction of swing of the pendulum, a circuit controller for controlling said electromagnets, said circuit controller comprising two sectors controlled by the pendulum 85 and three contact fingers, two of which are adapted to engage one sector and one of which is adapted to engage the other sector.

2. In combination, a pendulum, an electromagnet for actuating said pendulum to 95 swing in one direction, another electromagnet for actuating said pendulum to swing in the other direction, a circuit controller comprising contacts controlled by the pendulum for selecting one or the other of said electromagnets for energization, and an additional contact for controlling the period during 100 which one or the other of said electromagnets is energized.

3. In combination, a pendulum, an electromagnet for actuating said pendulum to swing in one direction, another electromagnet for actuating said pendulum to swing in the other direction, a circuit controller comprising a contact controlled by the pendulum 110 for controlling the portion of the pendulum stroke during which either one of the electromagnets may be energized, additional contacts controlled by the pendulum for selecting one or the other of said electromagnets 115 for energization, and means whereby one of said last-mentioned contacts is always closed.

4. In combination, a pendulum, an electromagnet for actuating said pendulum to swing in one direction, another electromagnet for actuating said pendulum to swing in the other direction, a circuit controller comprising a contact controlled by the pendulum for controlling the portion of the pendulum stroke during which either one of the electromagnets may be energized, additional contacts controlled by the pendulum for selecting one or the other of said electromagnets 120 for energization, and means whereby the time of open circuit caused by opening the 125

- circuit of one electromagnet and closing the circuit of the other electromagnet is made very small.
5. In combination, a shaft, a pendulum keyed thereto, two electromagnets for oscillating said shaft and pendulum, one for each direction of motion; a circuit controller comprising a sector rigidly mounted on said shaft and a contact finger for controlling the energization of either of said electromagnets, and another sector loosely mounted on said shaft and two contact fingers for selecting one or the other of said electromagnets for energization, stops for limiting the angle through which said second sector may be rotated with respect to said shaft, and means whereby said second sector is held in contact with one or the other of its contact fingers when the pendulum is in the middle of its stroke.
- 10 6. In combination, a pendulum, an electromagnet for actuating said pendulum to swing in one direction, another electromagnet for actuating said pendulum to swing in the other direction, a circuit controller comprising contacts controlled by the pendulum for energizing one or the other of said electromagnets, and an additional contact for controlling the period during which one or the other of said electromagnets is energized, and means whereby the contacts controlling one magnet or the other are closed when the pendulum is in the middle of its stroke, according as the pendulum approaches said middle point from one side or the other.
- 15 7. In combination, a pendulum, means for causing oscillation of said pendulum, and means for retaining said pendulum in an inclined position, said retaining means being resilient to gradually absorb the momentum of the pendulum when brought to rest.
- 20 8. In combination, a pendulum, means for causing oscillation of said pendulum, and means for retaining said pendulum in an inclined position, said retaining means comprising a latching member attached to the pendulum and another member movable into and out of the path of the latching member, one of said members being resilient to gradually absorb the momentum of the pendulum when brought to rest.
- 25 9. In combination, a pendulum, a member resiliently mounted thereon, a pawl on said member biased to an engaging position, a movable member, and an electromagnet for moving said member into the path described by said pawl when the pendulum oscillates.
- 30 10. In combination, a pendulum, engaging means resiliently mounted on said pendulum, a member adapted to be engaged by said means and biased to a non-engaging position, and an electromagnet for moving said member to an engaging position.

11. In combination, a base, a pendulum suspended therefrom, a member resiliently mounted on said pendulum, a pawl on said member, a stop for said pawl, means mounted on said base adapted to be engaged by said pawl, said means being biased to a non-engaging position, and an electromagnet mounted on said base for moving said means to an engaging position, so that said pawl can pass said means only in one direction.

12. A signal comprising a pendulum, a shaft to which said pendulum is fixed, a sleeve fixed on said shaft and having two engaging surfaces disposed on opposite sides of the shaft, two armatures pivotally mounted on said shaft, two electromagnets one for attracting each of said armatures, and a lip on each armature adapted to contact with one of the surfaces on the sleeve whereby the pendulum is swung in one direction or the other according to which magnet is energized.

13. A signal comprising a pendulum, two electromagnets one for giving said pendulum an impulse in each direction, means including circuit controlling contacts operatively connected with the pendulum for selectively energizing said electromagnets, means for retaining said pendulum in substantially one extreme position of its movement, and means operatively connected with the pendulum and acting before the pendulum reaches the said extreme position to deenergize the electromagnet which was last energized.

14. A signal comprising a pendulum, two electromagnets one for giving said pendulum an impulse in each direction, means including circuit controlling contacts operatively connected with the pendulum for selectively energizing said electromagnets, and means operatively connected with said pendulum for deenergizing both of said electromagnets when the pendulum swings a predetermined distance beyond its mididle position.

15. A signal comprising a pendulum, electromagnetic means for causing said pendulum to swing to and fro continuously, means operatively connected with said pendulum for deenergizing said electromagnetic means when the pendulum approaches each extreme position, and means for latching said pendulum in substantially an extreme position.

16. A signal comprising a pendulum, a pawl carried thereby, a member adapted to engage said pawl to latch the pendulum, and an electromagnet for moving said member into the path of said pawl.

17. A signal comprising a pendulum, a frame resiliently mounted thereon, a pawl pivoted in said frame, a member movable into and out of the path of said pawl, the

- movement of the pawl on its pivot being such that when the said member is in the path of the pawl the pawl can pass the member when the pendulum is swinging upwardly but not when the pendulum is swinging downwardly, and the resilient connection between the pendulum and the frame being such as to absorb the shock when the pendulum is caught by the pawl.
18. A signal comprising a pendulum, and means for latching said pendulum in an inclined position, said means including a resilient member to absorb the momentum of the pendulum when the latter is caught by said means.
19. A signal comprising a pendulum, electromagnetic means for causing said pendulum to swing to and fro continuously while said means is energized, and a latching device for holding said pendulum in an inclined position; said device comprising a latch on the pendulum, a member movable into and out of the path of said latch and biased to a position out of said path, and an electromagnet for moving said member into and holding it in the path of said latch when the electromagnet is energized.
20. A signal comprising a pendulum mounted to oscillate, two electromagnets, an armature for each electromagnet, means for operatively connecting each armature with the pendulum to drive the pendulum from an inclined position on one side or the other of the vertical to substantially the vertical position while the corresponding armature is moving toward the pole-piece of its electromagnet, said means providing for lost motion between the pendulum and each armature so that the pendulum may continue its swing after the armature which has acted upon the pendulum reaches its pole-piece, and means controlled by the pendulum for selectively energizing said electromagnets.
21. A signal comprising a pendulum mounted to oscillate, two electromagnets, an armature for each electromagnet, means for operatively connecting each armature with the pendulum to drive the pendulum from an inclined position on one side or the other of the vertical to substantially the vertical position while the corresponding armature is moving toward the pole-piece of its electromagnet, said means providing for lost motion between the pendulum and each armature so that the pendulum may continue its swing after the armature which has acted on the pendulum reaches its pole-piece, and means controlled by the pendulum for energizing said electromagnets and operating when the pendulum passes through substantially its vertical position to deenergize the electromagnet which has been acting on the pendulum and to energize the other electromagnet.
22. A signal comprising a pendulum mounted to oscillate, two electromagnets, an armature for each electromagnet, means for operatively connecting each armature with the pendulum to drive the pendulum from an inclined position on one side or the other of the vertical to substantially the vertical position while the corresponding armature is moving toward the pole-piece of its electromagnet, said means providing for lost motion between the pendulum and each armature so that the pendulum may continue its swing after the armature which has acted on the pendulum reaches its pole-piece, means controlled by the pendulum for energizing said electromagnets and operating when the pendulum passes through substantially its vertical position to deenergize the electromagnet which has been acting on the pendulum and to energize the other electromagnet, means for latching said pendulum in an inclined position, and means controlled by the pendulum and acting before the pendulum reaches the position in which it is latched for deenergizing the electromagnet which was last energized.
23. A signal comprising a pendulum mounted to oscillate, two electromagnets, an armature for each electromagnet, means for operatively connecting each armature with the pendulum to drive the pendulum from an inclined position on one side or the other of the vertical to substantially the vertical position while the corresponding armature is moving toward the pole-piece of its electromagnet, said means providing for lost motion between the pendulum and each armature so that the pendulum may continue its swing after the armature which has acted on the pendulum reaches its pole-piece, means controlled by the pendulum for energizing said electromagnets and operating when the pendulum passes through substantially its vertical position to deenergize the electromagnet which has been acting on the pendulum and to energize the other electromagnet, and other means controlled by the pendulum for deenergizing both of said electromagnets when the pendulum swings a predetermined distance beyond its vertical position.
